UNITED STATES PATENT OFFICE.

OLE EVINRUDE, OF MILWAUKEE, WISCONSIN, ASSIGNOR TO EVINRUDE MOTOR CO., OF MILWAUKEE, WISCONSIN.

CANOE AND OTHER SMALL CRAFT.

1,011,930.

Specification of Letters Patent. Patented Dec. 19, 1911.

Application filed May 9, 1911. Serial No. 625,949.

To all whom it may concern:

Be it known that I, OLE EVINRUDE, a citizen of the United States, and resident of Milwaukee, in the county of Milwaukee and

- 5 State of Wisconsin, have invented certain new and useful Improvements in Canoes and other Small Craft; and I do hereby declare that the following is a full, clear, and exact description thereof.
- 10 My invention consists in what is herein particularly set forth with reference to the accompanying drawings and pointed out in the claims of this specification, its object being to provide canoes and other small
- 15 craft with simple, economical and efficient propulsion mechanism similar in some respects to what is set forth in my application Serial No. 582,336, filed September 16, 1910, the mechanism herein described being
- 20 designed for ready detachable connection with a thwart and the bottom of the craft to which it is applied.

Figure 1 of the drawings represents a for the most part sectional view of propulsion mechanism in accordance with my invention applied to a canoe of which a fragment of the same is shown partly in section but otherwise in side elevation, the plane of the section being indicated by line 1—1 in Fig. 30 4; Fig. 2, a side elevation of a portion of said mechanism, a thwart to which it is connected being in transverse section, as indicated by line 2—2 in Fig. 4; Fig. 3, a plan view of a detail partly in horizontal section 35 on the plane indicated by line 3—3 in Fig. 1, and Fig. 4, a similar view, the section thereof being indicated by line 4—4 in Fig. 2.

Referring by numerals to the drawings, 5 40 indicates a canoe having a block 6 set in upon the bottom and ribs thereof under a thwart 7 for which supporting brackets 8 are provided in connection with certain of said ribs, said block being fastened by 45 screws or otherwise to the underlying ribs. Fitting alined central apertures in the canoe bottom, the block 6 and the thwart 7 is a cylindrical shell 9. Packing 10 surrounds the shell between said canoe bottom and 50 block, and other packing 11 surrounds said shell between said block and a flanged collar 12 bolted thereto, the packing serving to prevent leakage into the canoe. The upper end of the shell is externally screw- 55 threaded for the engagement of nuts 13,

that oppose the sides of the thwart 7 to thus secure said shell in place.

Bolted or otherwise rigidly secured on the thwart 7 is a pedestal bracket 14 to which a casing-extension 15' of the cylinder 15 60 of an internal-combustion engine is connected. As a matter of detail, the casing-extension of the engine-cylinder is provided with opposite lateral lugs 16 that are bolted to upwardly extending parallel arms 14' of 65 the aforesaid bracket, and said casing-extension of said engine-cylinder is also provided with bearings for the engine-shaft 17 having a crank thereof in rod connection with the engine-piston 18. A fly-wheel 17' 70 fast on the upper outer end of the engine-shaft, is provided with a handle 17" to facilitate cranking of the engine, and a liquid fuel tank 19 is shown conveniently arranged in connection with the casing-extension of the engine-cylinder. 75

Rigidly secured on one of the bearings for the engine-shaft is a depending tube 20 engaging another tube 21 that extends down through the shell 9 and is rigidly secured 80 at its lower end to a gear-case 22. The upper ends of the tubes 20 and 21 are immediately under the casing-extension of the engine-cylinder, and in gripping connection with said tube 21 between the shell 9 and 85 said extension of the engine-cylinder is a split-ring end 23' of a tiller 23 for which a supporting rod 24 is provided in connection with the arms 14' of the pedestal bracket on the thwart aforesaid. As a matter of detail, 90 the ring end of the tiller is provided with ears flanking its split and a clamping-bolt 25 engages the ears.

Rigidly secured on the lower end of the engine-shaft 17 is a sleeve-extension 26 provided with an inner spline 26' engaging a groove in an auxiliary shaft 27 for which a portion 22' of the gear-case 22 constitutes a bearing within the lower end of the tube 21. The shaft 27 is virtually a continuation of the engine-shaft, and its lower end is in inter-gear connection with the shaft 28' of a propeller 28, as shown in Fig. 1, the gear-case 22 being provided with bearings for the propeller-shaft. The propeller-hub 100 and the end of the gear-case farthest from said hub are preferably conical, as herein shown to offer the least resistance to water in which the canoe is floated, and said canoe 105 is preferably provided with a depending 110

fender 29 forward of the propeller. The extension 22' of the gear-case 22 being fast in the tiller-controlled tube 21, the propeller is made to serve as a rudder for said 5 canoe.

A pump-cylinder 30 is shown fitted to the gear-case 22 for connection, by a hose 31 with a pipe 32 that extends up through the canoe-bottom, the block 6, the flange of the 10 collar 12 and the thwart 7, the upper end of the pipe being connected by a hose 33 with the water-jacket of the engine-cylinder. The pump-piston 34 is operated by a cam 35 on the hub of the gear-wheel of the 15 propeller-shaft. Another hose 36 is employed in connection with an outlet of said water-jacket to conduct water therefrom overboard.

From the foregoing it will be readily 20 understood that the propulsion-mechanism may be readily detached from the canoe after loosening the tiller 23 on the shell 9 and uncoupling the hose 31 from the pipe 32, the tube 21 and parts therewith, including the shaft 27, being slipped away from 25 below, leaving the engine and parts therewith, including the tube 20, to be slipped away from above, after disconnecting said engine from the pedestal-bracket on the 30 thwart aforesaid.

While the foregoing has especial reference to canoes, my improvements herein disclosed apply also to skiffs, row-boats and other small craft for which propulsion 35 mechanism is desirable.

I claim:

1. The combination with a canoe or other small craft and a thwart therein, of a bottom-block underlying the thwart, a cylindrical shell secured in connection with the thwart and extended through said block and the bottom of said craft with which it has water-tight engagement, an engine supported in connection with said thwart above 40 the same, a tiller-controlled tube concentric with the engine-shaft and engaging said shell, and a propeller suspended in connection with said tube, the propeller-shaft being in gear with said engine-shaft.

2. The combination with a canoe or other small craft and a thwart therein, of a bottom block underlying the thwart, a cylindrical shell in connection with the thwart and extended through said block and the 45 bottom of said craft with which it has water-tight engagement, an engine supported in connection with the thwart above the same, a tube constituting an extension of a bearing for the engine-shaft, a tiller-controlled tube encompassing the tube aforesaid and engaging said shell, a sleeve constituting an extension of said engine-shaft to which it is fastened within the tube-extension of said bearing, an auxiliary shaft 50 in spline-connection with the sleeve, and a

propeller suspended in connection with the tiller-controlled tube, the propeller-shaft being in gear with the auxiliary shaft.

3. The combination with a canoe or other small craft and a thwart therein, of a bottom block underlying the thwart, a cylindrical shell extending through the thwart, block and bottom of the craft with which it has water-tight connection, nuts engaging the shell against the sides of said thwart, an engine supported in connection with said thwart above the same, a tiller-controlled tube concentric with the engine-shaft and engaging said shell, and a propeller suspended in connection with said tube, the propeller shaft being in gear with said engine-shaft. 70 75 80

4. The combination with a canoe or other small craft and a thwart therein, of a bottom block underlying the thwart, a cylindrical shell secure in connection with said thwart and extended through said block and the bottom of said craft with which it has water-tight engagement, a pedestal bracket fast on the aforesaid thwart, an engine in 85 connection with the arms of the bracket, a tiller-controlled tube concentric with the engine-shaft and engaging said shell, and a propeller suspended in connection with said tube, the propeller-shaft being in gear with 90 95 said engine shaft.

5. The combination with a canoe or other small craft and a thwart therein, of a bottom block underlying the thwart, a cylindrical shell secured in connection with said thwart and extended through said block and the bottom of said craft with which it has water-tight engagement, an engine supported in connection with said thwart above the same, a tube concentric with the engine-shaft and engaging the shell, a tiller having a split-ring end in gripping connection with the upper end of the tube, and a propeller suspended in connection with said tube, the propeller-shaft being in gear with 100 105 110 said engine-shaft.

6. The combination with a canoe or other small craft and a thwart therein, of a bottom block underlying the thwart, a cylindrical shell secured in connection with said thwart and extended through said block and the bottom of said craft with which it has water-tight engagement, a pedestal bracket fast on the aforesaid thwart, an engine in connection with arms of the bracket, a tube concentric with the engine-shaft and engaging said shell, a tiller attached to the tube, a tiller-support rod connecting the arms of said bracket, and a propeller suspended in connection with said tube, the propeller-shaft being in gear with the engine-shaft. 115 120 125

7. The combination with a canoe or other small craft and a thwart therein, of a bottom block underlying the thwart, a cylin- 130

drical shell secured in connection with said thwart and extended through said block and the bottom of said craft with which it has water-tight engagement, a pedestal bracket 5 fast on the aforesaid thwart, an engine in connection with arms of the bracket, a tube constituting an extension of a bearing for the engine-shaft, a tiller-controlled tube encompassing the tube aforesaid and engaging 10 said shell, a sleeve constituting an extension of said engine-shaft to which it is fastened within the tube-extension of said bearing, an auxiliary shaft in spline connection with the sleeve, and a propeller suspended 15 in connection with the tiller-controlled tube, the propeller-shaft being in gear with the auxiliary shaft.

8. The combination with a canoe or other small craft and a thwart therein, of a bottom-block underlying the thwart, a cylindri- 20

cal shell secured in connection with the thwart and extended through said block and the bottom of said craft with which it has water-tight engagement, an engine supported in connection with said thwart above the 25 same, a tiller-controlled tube concentric with the engine-shaft and engaging said shell, a propeller suspended in connection with said tube, the propeller-shaft being in gear with said engine-shaft, and a fender 30 for said propeller in connection with the aforesaid craft.

In testimony that I claim the foregoing I have hereunto set my hand at Milwaukee, in the county of Milwaukee and State of 35 Wisconsin in the presence of two witnesses.

OLE EVINRUDE.
